LOCKING HANDLE FOR DOORS
AND THE LIKE

Ralph H. Osborne, Altadena, Calif., assignor to
The R. H. Osborne Company, Altadena, Calif.,
a corporation of California

Application July 22, 1950, Serial No. 175,317

10. Claims. (Cl. 70—211)

1

My invention relates generally to locking-type handles for doors and the like, and more particularly to handles of this type adapted to operate a bolt or similar means designed to hold a door closed.

There has long been a need for a locking handle for doors and similar members of the general type used in garages, whether these doors be of the overhead type, the horizontally swinging type, or other form. Preferably such a locking handle should be one wherein the lock may be operated by the same key that operates the lock on the door of the adjacent dwelling, and additionally the installation of the lock should be simple. It is also clear that the lock should be rugged and not easily broken or jammed, since garages, being generally separated a short distance from a house, are often burglarized with very little effort or fear of detection on the part of the burglar. All of these desirable qualities indicate that considerable thought and attention must be given to the design of a satisfactory handle, and heretofore there have been few if any locking handles meeting all of these requirements.

Particularly in the case of overhead doors, it is desirable to have a generally L-shaped handle, with one leg of the L extending generally perpendicularly from the plane of the door, while the other leg of the L is spaced from the door and generally parallel thereto. In this manner, the handle is readily grasped and turned, even though the hands of the operator may be dirty or greasy, and furthermore the handle is of great convenience in lifting or otherwise opening the door. Some attempts have been made to use L-shaped handles of the general type used for automobile doors, but the general design of such handles, while very satisfactory for its intended purpose, does not meet the aforementioned requirements when applied to a garage door. Among the principal objections encountered when using automobile door handles are mounting difficulties, and, because of the size of the handle and its associated locking mechanism, the handle may not be operated by the same key as that which operates the doors of the dwelling.

With the foregoing in mind, it is therefore a major object of my invention to provide an improved locking handle for doors and the like.

Another object of my invention is to provide such a handle that is easily and quickly installed on doors of any normal size and type.

It is a further object of my invention to provide a locking handle of this type, the key of which may be the same key as that which oper-

2

ates the locks in the doors of the associated dwelling.

Still another object of my invention is to provide such a lock of simple and rugged construction, applicable to doors of any type, whether overhead doors, hinged doors, or horizontally sliding doors.

It is a still further object of my invention to provide a locking handle of this type making use of standard locks or tumbler mechanisms, and designed for both inexpensive and large-scale production.

These and other objects and advantages of my invention will become apparent from the following description of a preferred form thereof, and from the drawings illustrating that form in which:

Fig. 1 is a perspective view of the rear of a garage door, partially broken away, showing the installation of my improved locking handle on an overhead door;

Fig. 2 is a vertical sectional view taken through the axis of the handle, and showing the installation of the handle on a door;

Fig. 3 is a rear elevational view of the locking handle, showing the position of the various members when the handle is locked;

Fig. 4 is a view similar to Fig. 3, showing the parts in their unlocked position; and

Fig. 5 is a view of the back plate, taken at 5—5 in Fig. 2, showing the operating mechanism connected to the rear or inner end of the operating shaft.

Referring now to the drawings and particularly to Fig. 1 thereof, the numeral 10 indicates generally a door of any suitable type, here indicated as an overhead garage door, adapted to close against a header 11. The door is provided with suitable holding means 12, here indicated as the lock shown in my previously filed co-pending application, Serial No. 121,865, filed October 17, 1949, and entitled "Lock," though it is to be understood that any other suitable type of door and lock may be used as desired, making minor appropriate modifications. The lock 12 is normally resiliently urged to engaging position and is operated by a downward pull on some suitable means such as a tape 13, the lock and tape both being within the garage, as disclosed in my previously-mentioned co-pending application. At

its lower end, the tape 13 is connected to an operating arm 14, and by rotation of the arm, the tape is pulled downwardly to release the lock 12 and permit the opening of the door. The operating arm 14 is shown as mounted on a back plate

15 and engages an operating shaft 16 that extends through the door 10 for operation by a locking handle 22.

As more clearly indicated in Figs. 2 to 4, the locking handle 22 includes a housing 21 to which there is pivotally attached a handle member 22 engaging the end of the operating shaft 16 and pivotable about the axis of the latter. The housing 21 is generally oval in shape, with its major axis vertical, though it will be understood that any other appropriate shape may be used, the presently described shape being selected because of its simplicity and its generally pleasing appearance.

Centrally located in the upper portion of the housing 21 is a lock cylinder 23 of the well-known pin-tumbler type. Such cylinders are widely used in all types of locks, and in general the cylinders of various manufactures are interchangeable so that there is no difficulty in mounting the desired cylinder in the housing 21. Furthermore, the cylinders are conventionally used in the locks of dwellings, and by selecting the proper number of cylinders of the correct type, all of the locks of the dwelling and garage or other outbuildings may be operated by a single key. These cylinders, it will be understood, each have a core 24 that receives the key and may be rotated by the latter, and on the end of the core 24 I mount a cam 25. The core 24 is located below the axis of the cylinder 23, and the cam 25, which rotates about the axis of the core, is thus rotated eccentrically with respect to the axis of the cylinder to operate the holding mechanism in a manner hereinafter described. The cylinder 23 is held in the housing 21 by a set screw 26, the latter passing vertically through a wall of the housing to engage the lower surface of the cylinder, the head of the screw being covered by the handle 22 when the latter is installed.

As best seen in Fig. 2, the lower end of the housing 21 is stepped or set in to provide a recessed portion for receiving the upper or shaft end of the handle 22. As previously mentioned, the handle is generally L-shaped, having a rather narrow hand-receiving portion extending in a plane generally parallel to the plane of the door 10, and provided at its upper end with a hollow shaft or boss 30 shaped to receive the shaft 16. A pin, screw, or other suitable means (not shown) may be passed through the boss 30 and the shaft 16 to hold the two, and the boss extends through an opening 31 in the housing 21 located below the cylinder 23. The upper end of the handle 22 is spaced a slight distance from the wall separating the stepped portion of the housing from the upper portion containing the cylinder 23, and consequently freedom of movement of the handle is insured, while the set screw 26, holding the cylinder in place, is covered against unauthorized removal. In a similar manner, the handle 22 covers a screw 32 that holds the housing 21 to the door 10, thus preventing the unauthorized removal of the housing; while another screw 33, located at the upper end of the housing, likewise holds the housing to the door in a properly aligned manner, but is accessible at all times. From this it will be seen that it is necessary to remove the handle 22 in order to release the cylinder 23, or to remove the housing 21 from the door. Consequently, so long as the handle 22 is retained in position, it is impossible to remove either the housing or the cylinder without destroying one or both of them.

To prevent the unauthorized removal of the

handle 22, the boss 30 attached thereto is provided with a cam-shaped section 34 at its rear end, adjacent the door 10. For the major portion of its length, the boss 30 is cylindrical, but as indicated in Figs. 3 and 4, the cam-shaped portion 34 is provided with a lobe whose crest extends radially outward from the cylindrical surface, while a flattened, generally horizontal surface 35, such as formed by a notch is immediately adjacent the crest. The hole 31 receiving the boss 30 is generally cylindrical, but is provided with an axially extending groove to receive the crest of the cam-shaped portion 34, the groove being intermediate the normal circumferential positions of the cam so that the handle cannot be removed when in either of its two limiting positions. At any time the crest of the cam 34 does not align with the groove of the hole 31, the crest will bear against the wall of the housing 21, thus holding the handle properly aligned with the housing and, as hereinafter explained, preventing the removal of the handle except when the cam 25 of the cylinder 23 is in unlocked position.

Pivottally mounted on the rear of the housing 21 just below the cylinder 23 is a cam-actuated operator 36. The operator 36 is generally T-shaped, and in its locked position, the stem of the T projects vertically downward, while the arms forming the cross bar are substantially horizontal. At each end of the cross bar, there is a rearwardly extending surface such as that formed by a stud or projection, one stud 37 controlling the locking of the handle, and the other stud 38 controlling its unlocking. As an alternate construction, the operator 36 may be formed of thicker material, and its upper surface used instead of a separate projection. The operator 36 is pivotally connected to the housing 21 by a screw 40, and the screw is located vertically above the notch 35 in the cam-shaped portion 34 of the bushing 30 when the handle 22 is in its normal or vertical position. The stem of the T-shaped operator 36 extends vertically downward from the screw 40 when the operator is in locked position, but may be rotated from this position to the position shown in Fig. 4 when the handle assembly is unlocked. This rotation of the operator 36 is accomplished by the cam 25, as indicated in Figs. 3 and 4, where it will be seen that the cam 25 bears against the locking pin 37 to urge the latter downwardly when the device is in locked position. Rotation of the cam 25 in a clockwise direction, as seen in Figs. 3 and 4, shifts the cam to the opposite side of the housing 21 where it then bears against the unlocking pin 38, urging it downwardly and rotating the operator 36 in a clockwise direction as seen in Figs. 3 and 4.

When the operator 36 is in locked position, the lower end of the stem is aligned with the flattened surface 35 of the cam-shaped portion 34 of the boss 30, and any attempted rotation of the handle 22 in a clockwise direction, as seen in Figs. 3 and 4, causes the generally horizontal surface to be urged upwardly, against the lower end of the stem. However, since this upward force acts along a line passing through the center of the screw 40, the stem of the operator 36 remains stationary and prevents any rotation of the handle 22 in a clockwise direction. Rotation of the handle 22 in a counter-clockwise direction is prevented by the assembly associated with the back plate 15, hereinafter described, and consequently all rotation of the handle is prevented.

When the cam 25 is rotated in a clockwise

direction to the position shown in Fig. 4, this being done by the insertion of a key and the rotation of the core 24, the cam bears against the unlocking stud 38 and moves the operator 36 in a clockwise direction to the position shown in Fig. 4. In this unlocked position, the operator 36 has been rotated so that the stem portion thereof is swung clear of the surface 35 and the crest of the cam portion 34 of the boss 30, and consequently the handle 22 is free to be turned in a clockwise direction, as shown in Fig. 4. Normally, the handle 22 must be rotated approximately 90° to effect the release of the door 10 by the bolt or lock 12, though occasionally a greater or lesser amount of rotation is required.

In any event, the groove of the opening 31 is preferably intermediate the two limiting positions of the cam portion 34, so that in either the locked or unlocked position, the handle 22 is securely held.

It will be appreciated that in the description heretofore given, the terms "clockwise" and "counter-clockwise" apply to the rotation of the parts as illustrated in Figs. 3 and 4. These views, it is recalled, are taken from the rear of the lock, and consequently the relative direction of rotation will be reversed when viewing the lock from the front or handle side thereof. While the lock may be constructed to operate in either direction, most people are right-handed, and it is consequently more convenient for one to grasp the handle 22 with his right hand, and turn it in a counter-clockwise direction, this being the clockwise direction as viewed in Figs. 3 and 4.

The back plate 15 is mounted on the inside or rear of the door 10 and has an aperture therein to receive the shaft 16 and hold it for free rotation. A collar or other suitable device (not shown) is preferably held to the end of the shaft 16 to prevent the unintended withdrawal of the latter from the back plate 15, this forming an additional safeguard against the unauthorized removal of the handle 22 from the housing 21.

Spaced around the opening receiving the shaft 16 are a plurality of ears 50 that are struck forwardly, toward the door 10, from the plane of the back plate 15. The ears 50 are generally parallel to the plane of the back plate, but are spaced therefrom so that a thin metal collar 51, mounted upon the shaft 16, may ride between the adjacent surfaces of the ears and the back plate. The collar 51 preferably has the operating arm 14 formed integrally with it and the collar is held to the shaft 16 for rotation therewith. Generally, the shaft 16 will have a non-circular cross-section such as square, and consequently it is a simple matter to prevent rotation of the collar with respect to the shaft. Preferably, the hole in the collar 51 receiving the shaft 16 is formed by cutting the center of the solid collar to form a plurality of triangular ears that are struck forwardly to engage the sides of the shaft and additionally brace the collar and hold it against rotation with respect to the shaft.

By properly locating the ears 50 formed on the back plate 51, they will act as limit stops to prevent undesired rotation of the shaft 16. For example, as shown in Fig. 5, the uppermost ear 50 bears against the upper side of the operating arm 14 to prevent clockwise rotation of the arm from its upper position, shown in solid outline, corresponding to the locking position of the lock member 12, and corresponding to the vertical position of the handle 22. Similarly, the lowermost ear 50 prevents counter-clockwise rotation

of the arm 14 beyond that shown in dotted outline in Fig. 5, this position of the arm corresponding to the released or disengaged position of the lock 12. In this manner, rotation of the arm 14 may be held between predetermined limits, it being recalled that clockwise rotation of the arm 14, as shown in Fig. 5, corresponds to counter-clockwise rotation of the shaft 16 as shown in Figs. 3 and 4.

To install my improved locking handle, the housing 21 is mounted upon the outer face of the door 10 by the screws 32 and 33. Thereafter, a hole 53 is bored through the door 10 in the proper location, the hole being large enough to receive the shaft 16, and normally not being greater than one-half inch in diameter. By inserting the drill through the hole 31 of the housing 21, the proper alignment of the hole 53 is insured. The cylinder 23 is examined to make certain that it is in unlocked position, and the handle 22, to which is attached the shaft 16, is then inserted so that the boss 30 extends through the hole 31, the cam-shaped portion 34 of the boss sliding through the groove of the hole 31 until entirely within the housing 21, at which time the handle may be turned to its normal vertical position. Thereafter, the back plate 15, together with the collar 51 attached thereto, is mounted on the rear surface of the door 10, and the operating arm 14 is attached to the tape 13 or other operating mechanism of the lock. Finally, the retaining collar (not shown) is attached to the exposed end of the shaft 16, and the device is ready for operation. It will be noted that this installation requires only a single hole, the hole 53, to be drilled through the door, and the driving of two screws 32 and 33. Consequently, all work may be quickly and easily done by the average carpenter without the use of any special tools such as expansion bits, etc. Installation is thus a very simple matter, and requires a minimum of time.

In the operation of the device, the cam 25 is in the position shown in Fig. 3 when the locking handle is in locked position. In this condition, the locking stud 37 is urged downwardly by the cam 25, causing the stem of the operating member 36 to engage the notch 35 of the cam-shaped portion 34. Thus, rotation of the handle 22 in a counter-clockwise direction, as viewed from the exterior of the door, is prevented. At the same time, the upper ear 50 of the backing plate 15 engages the edge of the operating arm 14 to prevent clockwise rotation of the handle 22, and consequently no operation of the handle is possible. However, when the proper key is inserted in the core 24 of the cylinder 23 and turned in a counterclockwise direction, the cam 25 is rotated to the position shown in Fig. 4, the locking stud 37 is released, and the unlocking stud 38 is engaged by the cam 25 and urged downwardly, pivoting the operator 36 to the position shown in Fig. 4 where the stem of the operator is moved clear of the cam-shaped portion 34. The cam-shaped portion 34 and the boss 30 to which it is attached are thus free to rotate in a counter-clockwise direction, but are still held against rotation in a direction clockwise from their original positions, by the action of the uppermost ear 50 on the backing plate 15. However, counter-clockwise rotation of the handle 22 moves the operating arm 14 to the position shown in dotted outline in Fig. 5, thereby releasing the lock 12.

and permitting the opening of the door 10. In this connection, it will be realized that the horizontal position of the handle 22 is the most convenient for lifting an object such as a garage door, and consequently women and children will have no difficulty in operating a properly counterbalanced door provided with my improved locking handle.

If it is desired to change the cylinder 23, it is only necessary to remove the handle 22 from the housing 21, and loosen the set screw 26. The cam 25 is then rotated to a position where it extends substantially vertically, and it will be found that the circumferential edge of the cam has been shaped to coincide with the periphery of the cylinder 23 in this position so that the cylinder and cam combination may be easily slipped out of the housing. All standard cylinders of this type are provided with an operating plate on the rear or inward end of the core 24, and the operator 36 is so formed that the operating plate of a standard cylinder acts very satisfactorily as a cam, and consequently no transfer of the cam 25 is necessary. Thereafter, the new cylinder 23 is inserted in the housing 21, care being taken that the aligning and holding splines and grooves that are used with all such cylinders are properly aligned. The set screw 26 is then tightened, and finally the handle 22 replaced.

It will be appreciated that if the cylinder 23 is not desired, the locking action may be eliminated by providing a plug fitting within the housing 21 in the normal position of the cylinder, and acting to hold the unlocking stud 33 downwardly. However, this feature is usually not desired, except as a temporary expedient.

From the foregoing, it will be seen that I have provided an improved locking handle fully capable of achieving the objects and securing the advantages previously mentioned. However, it will be appreciated that those skilled in the art will be able to make changes in the device that do not depart from the invention herein defined. Consequently, I do not wish to be restricted to the particular form or arrangement of parts herein described and shown, except as covered by my claims.

I claim:

1. A locking handle of the class described which includes: a housing; a handle pivotally attached to said housing; a shaft attached to said handle for movement therewith, said shaft and handle acting as an integral unit having a flat cam-shaped portion within said housing; an operating member pivotally connected within said housing and having a flat stem selectively movable from a first position engaging said cam-shaped portion and preventing rotation of said handle and shaft, to a second position clear of said cam-shaped portion so that said handle and shaft may be rotated, said stem and cam portion being substantially perpendicular to a radius through the point of pivotal connection of said operating member in said first portion whereby the force exerted by said cam portion against said stem during attempted rotation of said handle acts only against the pivotal connection and said operating member is held against pivotal movement from said first portion; and locking means mounted in said housing having a cam connected thereto for selectively moving said operating member between said first and second positions.

2. A locking handle of the class described which includes: a housing; a handle pivotally

attached to said housing; a shaft attached to said handle for movement therewith, having a generally cylindrical portion that passes through an aperture in said housing with a cam-shaped portion within said housing, said cam-shaped portion including a flattened surface and an adjacent lobe, said lobe extending radially outward beyond said cylindrical portion, and said aperture having an axially extending groove therein circumferentially displaced from the normal position of said lobe for receiving the latter during the insertion and removal of said shaft with said handle attached thereto; an operating member within said housing selectively movable from a first position engaging said cam-shaped portion and preventing rotation of said handle and shaft, to a second position clear of said cam-shaped portion so that said handle and shaft may be rotated; and locking means mounted in said housing having a cam connected thereto for selectively moving said operating member between said first and second positions.

3. A locking handle of the class described which includes: a housing; a handle pivotally attached to said housing; a shaft attached to said handle for movement therewith, said shaft and handle acting as an integral unit having a flat cam-shaped portion within said housing; a pivoted operating member within said housing, rotatable about an axis generally parallel to the axis of rotation of said shaft and handle and having a flat engaging portion adjacent said cam-shaped portion, said operating member being selectively movable from a first position where said engaging portion engages said cam-shaped portion to prevent the rotation of said handle and shaft, to a second position where said engaging portion is removed from the path of said cam-shaped portion for the free rotation of said handle and shaft, said stem and cam portion being substantially perpendicular to a radius through the point of pivotal connection of said operating member in said first portion whereby the force exerted by said cam portion against said stem during attempted rotation of said handle acts only against the pivotal connection and said operating member is held against pivotal movement from said first portion; and locking means mounted in said housing having a cam connected thereto for selectively moving said operating member between said first and second positions.

4. A locking handle of the class described which includes: a housing; a handle pivotally attached to said housing; a shaft attached to said handle for movement therewith, said shaft and handle acting as an integral unit having a flat cam-shaped portion within said housing; a pivoted operating member within said housing, rotatable about an axis generally parallel to the axis of rotation of said shaft and handle and having a flat engaging portion adjacent said cam-shaped portion, said operating member being selectively movable from a first position where said engaging portion engages said cam-shaped portion to prevent the rotation of said handle and shaft, to a second position where said engaging portion is removed from the path of said cam-shaped portion for the free rotation of said handle and shaft, said stem and cam portion being substantially perpendicular to a radius through the point of pivotal connection of said operating member in said first portion whereby the force exerted by said cam portion against said stem during attempted rotation of said han-

idle acts only against the pivotal connection and said operating member is held against pivotal movement from said first portion; and locking means mounted in said housing having a portion rotatable with respect to said housing and having a cam connected to said rotatable portion for movement therewith, said cam being rotatable between a first and second position, and engaging said operating member for moving the latter between its said first and said second positions, respectively.

5. A locking handle of the class described which includes: a housing; a handle pivotally attached to said housing; a shaft attached to said handle for movement therewith, having a generally cylindrical portion that passes through an aperture in said housing with a flat cam-shaped portion within said housing; a pivoted operating member within said housing, rotatable about an axis generally parallel to the axis of rotation of said handle, and having a flat portion engageable with said cam-shaped portion, said operating member having locking and unlocking sections positioned so that pressure on said locking section rotates said operating member to move said engageable portion into engagement with said cam-shaped portion, preventing rotation of said cam-shaped portion and said handle, said engageable portion and said cam-shaped portion being substantially perpendicular to a radius through the point of pivotal connection of said operating member so that the force exerted by said cam-shaped portion against said engaging portion during attempted rotation of said handle acts along a line passing through the point of pivotal connection of said operating member to said housing, while pressure on said unlocking section rotates said operating member to a position where the engaging portion thereof is removed from the path of said cam-shaped portion, whereby said handle is freed for rotation; and locking means mounted in said housing having a portion rotatable with respect to said housing and having a cam connected to said rotatable portion of said locking means for rotation therewith, said cam being rotatable between a first position where it bears against the locking section of said operating member to move said engaging portion thereof into engagement with said cam-shaped section, and a second position where said cam bears against said unlocking section to move said engaging portion out of the path of said cam-shaped section.

6. A locking handle of the class described which includes: a housing; a handle pivotally attached to said housing; a shaft attached to said handle for movement therewith, having a generally cylindrical portion that passes through an aperture in said housing with a cam-shaped portion within said housing, said cam-shaped portion including a flattened surface and an adjacent lobe, said lobe extending radially outward beyond said cylindrical portion, and said aperture having an axially extending groove therein circumferentially displaced from the normal position of said lobe for receiving the latter during the insertion and removal of said shaft with said handle attached thereto; an operating member within said housing for selectively engaging and disengaging said cam-shaped portion, said operating member preventing the rotation of said shaft when engaging said cam-shaped portion; and locking means mounted in said housing for selectively moving said operating means between engaging and disengaging positions.

7. A locking handle of the class described which includes: a housing; a handle pivotally attached to said housing; a shaft attached to said handle for movement therewith, having a generally cylindrical portion that passes through an aperture in said housing with a cam-shaped portion within said housing, said cam-shaped portion including a flattened surface and an adjacent lobe, said lobe extending radially outward beyond said cylindrical portion, and said aperture having an axially extending groove therein circumferentially displaced from the normal position of said lobe for receiving the latter during the insertion and removal of said shaft with said handle attached thereto; a pivoted operating member within said housing, rotatable about an axis generally parallel to the axis of rotation of said shaft and handle and having an engaging portion adjacent said cam-shaped portion, said operating member being selectively movable from a first position where said engaging portion engages said cam-shaped portion to prevent the rotation of said handle and shaft, to a second position where said engaging portion is removed from the path of said cam-shaped portion for the free rotation of said handle and shaft; and locking means mounted in said housing having a portion rotatable with respect to said housing and having a cam connected to said rotatable portion for movement therewith, said cam being rotatable between a first and second position, and engaging said operating member for moving the latter between its said first and said second positions, respectively.

8. A locking handle of the class described which includes: a housing; a handle pivotally attached to said housing; a shaft attached to said handle for movement therewith, having a generally cylindrical portion that passes through an aperture in said housing with a cam-shaped portion within said housing, said cam-shaped portion including a flattened surface and an adjacent lobe, said lobe extending radially outward beyond said cylindrical portion, and said aperture having an axially extending groove therein circumferentially displaced from the normal position of said lobe for receiving the latter during the insertion and removal of said shaft with said handle attached thereto; a pivoted operating member within said housing, rotatable about an axis generally parallel to the axis of rotation of said handle, and having a portion engageable with said cam-shaped section, said operating member having locking and unlocking sections positioned so that pressure on said locking section rotates said operating member to move said engageable portion into engagement with said cam-shaped section, thereby preventing rotation of said cam-shaped portion and said handle, the force exerted by said cam-shaped portion against said engaging portion during attempted rotation of said handle being along a line passing through the point of pivotal connection of said operating member to said housing, while pressure on said unlocking section rotates said operating member to a position where the engaging portion thereof is removed from the path of said cam-shaped section, whereby said handle is freed for rotation; and locking means mounted in said housing having a portion rotatable with respect to said housing and having a cam connected to said rotatable portion of said locking means for rotation therewith, said cam being rotatable between a first position where it bears against the locking section of said operating member to move said engaging portion thereof into engagement with said cam-shaped portion.

11

cam-shaped section, and a second position where said cam bears against said unlocking section to move said engaging portion out of the path of said cam-shaped section.

9. A locking handle of the class described which includes: a housing adapted to be mounted on the flat surface of a door, and having a recessed portion and a raised portion, each of said portions having an aperture therein; a handle having at least one end thereof in said recessed portion of said housing; a shaft attached to said handle for movement therewith and extending through said aperture in said recessed portion, said shaft being substantially cylindrical adjacent said handle, and said aperture receiving said shaft being substantially cylindrical but with an axially extending groove therein; a cam section on said shaft within said housing, having a flattened surface and an adjacent lobe extending radially outward beyond the periphery of said cylindrical portion of said shaft, said lobe and said groove in said aperture being complementary so that said cam section may be moved axially through said aperture; a generally T-shaped operating member pivotally mounted within said housing, having a downwardly projecting stem portion selectively movable to engage said cam section or to be removed from the path of said cam section, and having a generally horizontal cross-bar section, one end of which is a locking end, and the other end is an unlocking end, said operating member being pivoted for movement about an axis generally parallel to the axis of said shaft, whereby pressure directed toward said stem and applied to said locking end urges said stem into engagement with said cam section to hold the latter and said shaft against rotation, while said pressure applied to said unlocking end moves said stem out of said path of said cam section to release the latter and said shaft for limited rotation; a lock cylinder mounted in said aperture in said raised portion of said housing and

12

held against rotation with respect thereto, said cylinder having a key-receiving core rotatable with respect to said cylinder upon the insertion of the proper key within said core; and a cam member attached to said core for movement therewith, said cam member being adjacent said operating member and rotatable between a position where it bears against the locking end of said operating member, and a position where it bears against the unlocking end of said operating member, said cam member thereby effecting the locking and unlocking of said shaft.

10. A locking handle as defined in claim 9 in which said lobe of said cam section is in a first position when said stem engages said flattened surface to hold said shaft against rotation, and said lobe is in a second position, angularly displaced from said first position, when said shaft is rotated to a position effecting the operation of a connected device, and said groove in said aperture is intermediate said first and second position of said lobe, and further defined by the fact that pressure exerted by said cam section upon the stem of said operating member, upon attempted rotation of said shaft while said stem is in locked position, is in a line passing through said stem and the axis of rotation of said operating member.

RALPH H. OSBORNE.
